Filed Oct. 5, 1966, Ser. No. 584,551

1 Claim. (Cl. 58—128)

ABSTRACT OF THE DISCLOSURE

A watch dial assembly automatically effecting periodic annular unidirectional shifting of a movable dial relative to a fixed dial to present, sequentially, through windows formed in the fixed dial, first and second sets of hour markers carried by the movable dial.

This invention relates generally to improvements in timepieces such as clocks, watches, and similar time keeping instruments. More particularly, the invention is directed to improvements in clocks, watches, and the like by means of which visual reading of the dial is facilitated. Specifically, the present invention has for its primary purpose the provision of improved means by which a watch or clock dial may be easily read, not only during the daylight hours but at night as well.

A principal object of the present invention is to provide in a timepiece automatic means operative to effect a dial shifting whereby either of two complete sets of hour indicators or markers may be viewed, selectively, on the face of the timepiece, one of the sets of markers being specially adapted for night time viewing.

A related object of the invention is to provide a timepiece including two complete sets of hour markers positionable automatically to be viewed selectively and in which one set of markers may be any preferred type while the second set of markers comprises luminous symbols adapted for viewing at night or under conditions of limited illumination.

Yet another object of the invention is to provide a timepiece which includes, in a double dial system, a first dial movable arcuately with respect to a second dial for displaying, through the second dial, either of two sets of hour markers carried by the first dial.

Yet another object of the invention is to provide a watch movement which includes a dial carrying hour indications or markers arranged to form two sets, one set being suitable for day-time viewing and the other set being specially adapted for night-time viewing.

A related object of the invention is to provide a timepiece in which the hour markers comprise two complete sets arranged in alternation and carried on a movable dial, disc or ring positioned below or beneath a fixed dial or watch face, the latter being provided with twelve openings, windows, or apertures through which either series of markers may be viewed, selectively, at predetermined time periods.

Another object of the invention is to provide means for automatically shifting the hour-indicating means, and in which the shifting occurs every twelve hours.

A related object of the invention is to effect the dial shifting through the driving medium of the clock mechanisms itself, without any major alteration in the watch movement.

Other and further objects, advantages, and features of the invention will become apparent from the reading of the following specification taken in conjunction with the drawing, in which:

FIGURE 1 is a perspective view of a wrist watch having day and night hour indicators embodying the present invention;

2

FIGURE 2 is a face view of a timepiece and illustrating schematically the annularly disposed spaced openings in the fixed dial with one end of movable dial-carried markers visible through the openings in the fixed dial;

FIGURE 3 is a face view similar to FIGURE 2, portions of the fixed dial being broken away to illustrate, schematically, one form of the movable dial-shifting mechanism therebeneath;

FIGURE 4 is an enlarged vertical cross-sectional view taken substantially on the line 4—4 of FIGURE 3 and showing a gear train assembly and associated cam and detent mechanisms whereby automatic periodic advance of the movable dial is achieved; and

FIGURE 5 is an enlarged cross-sectional view taken substantially on the line 5—5 of FIGURE 3.

The aims and objects of the invention are accomplished by providing, in a timepiece such as a watch, a main dial or face plate with twelve cut outs or windows circumferentially spaced in a peripheral annular zone of the dial, at positions of the hours. A second dial or disc, rotatably supported beneath the watch face, carries hour markings in two sets equally spaced around the movable dial, the hour markings of one set being alternately arranged in relation to those of the other set. Finally that is provided automatic means for shifting or rotating the movable dial, periodically and incrementally, to present, alternately, either of the two sets of markings through the cut outs or windows of the watch face.

The illustrative example provided in the drawings shows one form of means for effecting the change from one set of hour indications to the other, automatically. The timepiece itself contains clock-work mechanism of the usual type well known in the art; the mechanism is, therefore, not illustrated. The clock-work mechanism may be either mechanically or electrically operated, a mechanically operated mechanism being indicated more or less diagrammatically as its particular form does not constitute an essential part of the invention and needs no description here beyond an indication of the functional linkage.

Referring more particularly, to the drawing, there is shown in FIGURES 1, 2 and 3, and particularly in FIGURES 2 and 3, for purposes of disclosure, a watch 10 incorporating the teachings of the invention. In the simple exemplary embodiment of the invention illustrated, the watch 10 is provided with a generally circular face plate or dial 14 which is fixedly in position, in the usual manner. The fixed dial 14 overlies and serves to mask a second dial or a ring 18 coaxially disposed with respect to the face plate 14 and rotatably mounted for controlled arcuate movement.

The rotatable dial or ring 18, in the simple form of the invention shown, bears two sets of hour indications or markers 22 and 24 equally spaced around its margin, the hour markers of one set being alternately arranged in relation to those of the second set, as indicated schematically in FIGURE 3. One set 22 of the markers may take any preferred form or color consistent with easy day-time visibility. However, the indications or markers 24 of the second set are coated with a radium-salt-containing preparation or other material which emanates energy to fluoresce or otherwise to be rendered visible under limited illumination and even in darkness.

As shown in FIGURES 2 and 3, the face plate 14 is provided with twelve openings, windows, cut outs, or apertures 28 spaced circumferentially in a peripheral annular zone of the face plate and located at the positions of the hours of an ordinary dial. Thus, through annular movement imparted at controlled time intervals to the rotatable ring 18, by mechanism operated by the clock movement, first one series or set 22 of hour markers is

positioned behind and in coincidence with the openings 28 and at a later period, upon incremental shifting of the movable dial or ring 18, the second set or series 24 of hour markers is caused to appear through the cut outs or windows 28. It is contemplated that, for a preferred embodiment of the invention, the time periods allocated to each of the hour marker series 22 and 24 will be of equal duration and that shifting from one set of markers to the other will occur every twelve hours. For example, in a preferred arrangement of gearing and cams, the daylight markers 22 would be visible through the windows 28 from the hours 6 a.m. to 6 p.m. while the "radium" treated set of markers 24 would be visible through the same windows 28 during the hours from 6 p.m. until 6 a.m.

The manner in which the rotatable ring 18 is periodically shifted, automatically, is described below with reference to FIGURES 3 and 4. As illustrated schematically in FIGURE 4, the rotatable ring 18 seats within and is slidably or rotatably carried in an inwardly opening endless annular channel or slot or slideway 32 formed in a cooperating circumscribing annular bearing 40.

The movably supported ring 18 is integrally formed with and carries on its inwardly extending face a number of regularly spaced teeth 44, which, in the specific embodiment of the invention illustrated, are 24 in number. Thus, upon successive advances, step-wise, the extent of arcuate or angular movement of the ring 18 corresponds to half the angular distance or half the arc distance between successive or adjacent openings 28 in the face plate 14. Through this simple arrangement, each step-wise displacement of the movable ring 18 effects a shift, arcuately, of the ring 18 so that, alternately, the two different sets 22 and 24 of hour markers are brought into coincidence with the apertures 28 of the watch face plate 14.

The periodic, angular, incremental shifting of the hour marking ring 18 may be effected through any preferred mechanical means, one such suitable mechanism being illustrated schematically in FIGURES 3 and 4. As shown, angular displacement of the ring 18 is achieved by means of a tooth-engaging cam 48 which is mechanically coupled with and actuated through a train of gear wheels 52. A gear wheel 56, fixed on the hour hand spindle 60, meshes with a second gear wheel 62 rotatably supported on a pin or shaft 66 suitably carried on the watch frame, and a gear 70 mounted coaxially with the gear wheel 62 meshes with still another wheel 74 mounted on a spindle 80. The cam 48 is mounted on this same spindle 80 and rotates with the gear wheel 74. The gear wheel diameters in the gear train 52 illustrated are such that the gear wheels 74, and its associated cam 48, make one-half revolution for each revolution of the gear wheel 56 and, thus, of the hour hand 84. As shown in FIGURE 3, the cam 48 is formed with two diametrically opposed projections 90 and 90a extending radially outwardly of the periphery 94 of the body of the cam 48 in positions to come into abutment with and positively to engage the teeth 44 of the ring 18, as the cam 48 rotates.

It will be apparent that, in consequence of the arrangement described, for each rotation of the hour hand 84, or at 12-hour intervals, there will be a single stepping or incremental shifting of the movable ring 18. Since, as previously described, the movable ring 18 carries 24 teeth, each shift of the ring will correspond to half of the arcuate distance between adjacent or successive windows 28 in the face plate 14 and, with each incremental angular shift, a given set of markings 22 will be shifted from its position of coincidence with the windows 28 and the other set 24 of markers will be shifted into coincidence so as to be viewed through the apertures 28.

As shown in FIGURE 3, dial detent means are provided in order to preclude inadvertent shifting of the movable ring 18 and further to establish positive mechanical action. A pawl 100 pivotally mounted on a pin 104 is yieldingly and resiliently urged radially outwardly of

the watch center by means of a spring 108 so that the free end of the pawl 100 stresses against and rides upon the teeth 44 carried by the ring 18. A tongue portion 112 of the pawl extends into a notch 116 formed between two adjacent teeth, and edge portions 120 and 124 of the pawl abut edges of the respective adjacent teeth, whereby the ring 18 is restrained against accidental movement and firmly held in place until stepped in response to the positive action imparted by the cam 48. When either tooth-engaging projection 90 or 90a carried by the cam 48 engages a ring tooth 44 and acts to shift the ring 18 angularly, the arcuate force applied against the tooth 44 is sufficient to cause displacement of the pawl 100 and to pivot the pawl inwardly against the pressure of the spring 108. As a result, with clockwise rotation of the cam 48, the tooth 44 slides along the edge portion 124 of the pawl until the tongue 112 of the pawl drops into the next adjacent notch 116, thus establishing a full, one-step, incremental shift of the ring 18. Incremental angular shifting is repeated every twelve hours.

It is believed that the invention and its numerous attendant advantages will be fully understood from the foregoing description, and it is obvious that numerous changes may be made in the form, construction, and arrangement of the several parts without departing from the spirit and scope of the invention or sacrificing any of its attendant advantages, the form herein disclosed being a preferred embodiment for the purpose of illustrating the invention.

What is claimed is:

1. In a timepiece including a clock mechanism, a dial mechanism and hour-marking assembly providing improved day-time and night-time viewing and comprising, in combination,
- 35 a fixed dial having twelve apertures circumferentially and regularly spaced in a peripheral annular zone of said fixed dial,
- 40 a movable rotatably-supported dial coaxial with said fixed dial and positioned therebeneath,
- 45 a ring of teeth integrally formed with said movable dial, a cam rotated by the clock mechanism, and projection means carried by said cam and rotatable therewith, said projection means engaging cooperating said teeth of said movable dial to shift said movable dial angularly in incremental steps at predetermined time intervals,
- 50 means for automatically effecting periodic unidirectional rotary shifting of said movable dial at predetermined time intervals and comprising detent means retaining said movable dial firmly fixed in position against inadvertent movement until positive action of said cam effects precisely-controlled incremental arcuate shifting of said movable dial, said detent means comprising, in combination, a pivotally-mounted pawl, and spring means yieldingly and resiliently urging said pawl against said ring of said movable dial, said spring means firmly stressing said pawl against said teeth of said ring yet responsive to opposing forces transmitted thereagainst through said cam to permit arcuate displacement of said movable dial in finite fixed steps, said steps being defined by spacing of adjacent said teeth of said ring and corresponding to one-half of the arcuate separation between adjacent said regularly spaced apertures of said fixed dial,
- 55 two separate complete series of twelve-hour markers carried circumferentially on said movable dial adjacent the periphery thereof, said series being positioned coaxially and at the same radial distance from a center of said movable dial, said radial distance corresponding to a radial distance of said apertures from a common axis of said fixed and said movable dials,
- 60 the twelve hour markers of one said series being arranged in alternation with respective corresponding

twelve hour markers of the other said series, and a luminous coating applied to one said series to facilitate viewing of said markers during night-time periods, each said series of markers being adapted to be displayed selectively through said apertures, whereby during the first controlled time period a corresponding one of said series of markers is exposed through said apertures, while during a subsequent predetermined time period the other said series of markers is exposed through said apertures, the time period of exposure of each said series of markers be-

ing correlated respectively with nominal day-light and night-time periods.
